(57) **CLAIM**

The ornamental design for a pillowcase, as shown and described.

DESCRIPTION

FIG. 1 is bottom plan view of the pillowcase;

FIG. 2 is a top plan view of the pillowcase;

FIG. 3 is a front elevational view of an embodiment of a pillowcase;

FIG. 4 is a rear elevational view of the pillowcase;

FIG. 5 is a left side elevational view of the pillowcase; and, FIG. 6 is a right side elevational view of the pillowcase.

The broken lines shown in FIGS. 1-6 are included for the purpose of illustrating environmental elements only and form no part of the claimed design. The hook and loop fasteners shown in FIG. 3 form no part of the claimed design.
